UNITED STATES PATENT OFFICE

EDWARD C. MAY, OF CAMPAGAW, NEW JERSEY

CLOSURE FASTENER

Application filed November 18, 1927. Serial No. 234,177.

This invention relates to closure fasteners for vanity cases.

A general object of the invention is to provide a device which can be easily and economically manufactured and which will efficiently perform its function.

Another object of the invention is to provide a closure fastener for vanity cases which is light and compact, and the operating mechanism of which is peripherally disposed with respect to each of said annular members whereby there is a minimum obstruction of the area enclosed by said members and which will form a smooth external peripheral union.

15 A more specific object of the invention is to provide a vanity case having a closure fastener, the operative means for which is substantially concealed.

Other objects of the invention will in part 20 be obvious and will in part appear herein-after.

The invention accordingly comprises the several steps and the relation and order of one or more of such steps with respect to each 25 of the others, and the article possessing the features, properties and the relation of elements which are exemplified in the following detailed disclosure, and the scope of the application of which will be indicated in the 30 claims.

For a fuller understanding of the nature and objects of the invention reference should be had to the following detailed description taken in connection with the accompanying 35 drawings, in which:

Figure 1 shows a quartered elevational view of one embodiment of the device in open position;

40 Figs. 2 and 3 are similar views of other embodiments of the invention;

Fig. 4 is a vertical transverse sectional view of the form shown in Fig. 1;

Fig. 5 is a view similar to Fig. 4, of the form shown in Fig. 3; and

45 Fig. 6 is a perspective elevational view of the parts of the device shown in Fig. 3 in assembling position.

50 Although, as indicated above, the principles of the present invention may be employed to advantage in numerous different

associations, nevertheless they are particularly adaptable to vanity cases and the like, and, for the purpose of convenience, in the drawings the invention has been shown applied to such devices.

55 In the embodiment shown in the drawing, the numerals 10 and 11 designate respectively lower and upper annular members which are swingingly associated with respect to each other, as by a hinge 12 applied at one side. This hinge may be of any desired construction, but preferably contains a spring-member 13, which urges the members 10 and 11 toward open position, and is formed with 60 abutment shoulders 14 to prevent the members being opened beyond approximately a right angle.

65 In the form shown in Figs. 1 and 3, the member 10 is closed at the bottom and has an upwardly-spun lip 15, which bears a pair of diametrically-opposed outwardly-projecting lugs 16 which are engaged by the closure operating means carried by the swinging member 11, as will be hereinafter described; 70 while in the form shown in Fig. 2 the lugs 16 are replaced by a pair of bayonet-slots 17. As will readily be understood, either the slot or the lug-members may be disposed parallel to the member 10, as shown at 16, or may be 75 inclined, as shown at 17, so as to tend to wedge the members 10 and 11 more tightly toward each other as the locking action is effected.

80 In each of the embodiments shown in Figs. 1, 2 and 3, the upper swinging member 11 carries an internally-disposed annular ring 18, which bears internally-projecting lugs or pins 19 and is rigidly connected to a movable top 20 having a rim or edge 21 whereby when 85 the top 20 is rotated in a counterclockwise direction the members 19 are brought out of engagement with the locking members on the lip 15, thus allowing the swinging members 10 and 11 to be swung away from each other, 90 and when the members 10 and 11 are brought adjacent one another, and the top 20 is rotated in a clockwise direction, the locking members 19 are brought into engagement 95 with the locking members on the lip 15, 100

whereby the members 10 and 11 are held in closed position.

It will thus be seen that there has been provided a closure fastener which occupies a minimum amount of space and the parts of which are so disposed with respect to the swingingly-mounted annular members that the area bounded by the same is obstructed only to a very small extent. This is desirable in vanity cases, particularly since it increases the capacity and allows of placing a mirror or other cosmetic aid in the upper portion of the vanity case, and is also desirable when the closure fastener is used on other devices, such as automobile headlights and the like, in which case, as will be readily understood, the central portion of the top 20 might be cut away, leaving only the operating rim 21. Also, if desired, in vanity cases this operating rim may bear a lug 21', which aids in the movement thereof and, in certain assemblages, serves to give the device a somewhat more distinctive appearance.

Although the embodiment shown in Fig. 3 may be made in a number of ways, a preferred method of making the same is as is shown in Fig. 6. First, there is formed the lower annular member 10 having the spun-up lip 15 and the projecting lugs 16 or bayonet-slots 17, as desired. Next, there is provided the ring-portion 11' of the swinging member 11; both this portion and the previously-mentioned portion being provided with the hinge-members 12' ultimately forming the hinge 12. 35 There is next provided a ring-member 22, which is cut away on the inside of its lower and upper edges to form shoulders 23 and 24 respectively, and which is adapted to fit somewhat loosely within the ring-member 11' 40 which at its upper edge bears an upwardly-extending flange 25. A plurality of members 26, which are substantially U-shaped, are then mounted on that portion of the ring-member 22 which bears the shoulders 23 and 24, and 45 the end-portions thereof are then turned inwardly as at 27, whereby the members 26 are securely but slidably held onto the ring-member 22. The members 26 are then distributed circumferentially of the ring 22, the assembly 50 is placed within the ring 11', and the members 26 are welded, soldered or otherwise secured thereto. Thereafter, the top-member 20 is similarly affixed to the upwardly-extending flange 25, and the locking-members 19 are af- 55 fixed to the lower edge of the ring 22, whereby the spaced members 26 coact with the members 19 to limit the circumferential movement of the ring 22 and of the top 20 associated therewith.

60 In the form of device shown in Figs. 1 and 2, the assemblage is more simple, in that the internally-disposed ring 18 is held within the ring-member 11', and the rotative movement between the same is limited by means of pins 65 27 cooperating with slots 28. Here, however,

as in the form shown in Fig. 1, the upper edge of the ring 18 is attached to the top 20 and is rotatively moved thereby.

By utilization of the principles of the present invention, there may be provided a closure fastener for annularly-formed and swingingly-associated members which may be easily actuated to effect an opening or closing of said members with respect to each other, and the operating mechanism for which is so constructed and disposed as to neither obstruct the area enclosed by said annular members nor to modify the external appearance of the assemblage. When applied particularly to a vanity case, the present closure fastener gives a maximum capacity, an effective and easily operable closing and opening mechanism, and a refined internal and external appearance which is unencumbered by any bulky and unattractive mechanism for operating the same.

Although reference has been made to upper and lower members, etc., it is to be understood that these are merely relative terms and that a transposition of parts is obviously within the spirit of the invention. Also, since certain other changes in carrying out the above process, and certain modifications in the article which embody the invention may be made, without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. A vanity case, comprising, in combination, a shallow annular member closed at one end to provide a bottom, and at its other end having an extending lip carrying an outwardly- and radially-disposed projection; a second shallow annular member swingingly disposed on said first-mentioned annular member and adapted to mate therewith to form a smooth peripheral union, said second-mentioned annular member carrying an internally-disposed annular ring movable circumferentially with respect to said second-mentioned annular member and having an internally- and radially-disposed projection adapted to cooperate with said first-mentioned projection, and a top member operatively connected with said annular ring and movable with respect to said second-mentioned annular member.

2. A vanity case, comprising, in combination, a shallow annular member closed at one end to provide a bottom, and at its other end

having an extending lip of smaller diameter than the annular member; a second shallow annular member swingingly disposed on said first annular member and adapted to mate therewith to form a smooth peripheral union, 5 said second annular member carrying an internally-disposed annular ring movable circumferentially with respect thereto and adapted to fit over said lip, and a top member 10 operatively connected to said annular ring and movable with respect to said second mentioned annular member; said annular ring having an internally- and radially-disposed projection, and said lip being provided with 15 means to cooperate with said projection when said annular ring is moved in one direction to hold the vanity case closed.

In testimony whereof I affix my signature.
EDWARD C. MAY.
